UNITED STATES PATENT OFFICE.

ORLANDO KLING, OF DENVER, COLORADO.

BLOTTER AND RULER.

1,294,478.

Specification of Letters Patent. Patented Feb. 18, 1919.

Application filed April 16, 1918. Serial No. 228,890.

To all whom it may concern:

Be it known that I, ORLANDO KLING, a citizen of the United States, residing at Denver, in the county of Denver and State 5 of Colorado, have invented certain new and useful Improvements in Blotters and Rulers, of which the following is a specification.

This invention relates to a combined ruler and blotter support and has for its object 10 to provide a comparatively simple and inexpensive device of this character in which the parts may be readily assembled and the blotter elements renewed when impaired.

With this and other objects in view, the 15 invention consists in certain novel features of construction, as hereinafter shown and described and then specifically pointed out in the claims; and in the drawings illustrative of the preferred embodiment of the 20 invention—

Figure 1 is a perspective view of the improved device.

Fig. 2 is an enlarged front elevation with a portion in section on the line 2—2 of 25 Fig. 1.

Fig. 3 is a sectional detail on the line 3—3 of Fig. 2.

Fig. 4 is a detached perspective view, enlarged, of one of the clamp members.

The improved device comprises a body 30 portion 10 having one edge 11 continuous from end to end and constituting a rule edge. The portion of the body 10 opposite the rule edge 11 is bent at right angles 35 to the body as shown at 12, and the free edge of the portion 12 turned over as shown at 13 to form a longitudinally directed guideway. Connected to the upturned portion 12 of the body and spaced from its ends 40 are laterally directed stop pins 14. Clamp devices form a part of the improved device and are each formed from a strip of sheet metal comprising a body portion 15, a downturned edge 16 and an upturned portion 17, 45 the latter having a longitudinally directed open slot 18. One of the clamp devices will be employed at each end of the body and are precisely alike except that they are formed rights and lefts, or with the slots 18 open- 50 ing inwardly or toward each other as shown in Figs. 1 and 2. The clamp devices are designed to bear above the upper face of the body portion 10 with the upper edges of the portions 17 bearing within the guideway 55 13 and the slots 18 engaging over the pins 14, the latter being headed to hold the clamp

devices in position. The downturned edge 16 engages over the upper face of the body 10 adjacent to the rule edge 11. The blotter element is formed in strips 19 slightly 60 less in width than the body 10 and are superimposed and bear beneath the lower edge of the latter with the terminal portions bearing over the body 10 at its ends and beneath the body portions 15 of the clamp 65 devices as shown in Figs. 1 and 2. To assemble the parts the clamp devices are detached and the body 10 disposed in position above the strips of the blotting material with the ends of the latter extending beyond 70 the ends of the body 10. The projecting ends of the blotter elements are then folded over the ends of the body 10 and the clamp devices arranged in position with the portions 15 of the clamp devices bearing upon 75 the turned-over portions of the blotter strips and the downturned edge 16 in advance of the turned-over blotter portions and the portions 17 of the clamp devices forced into the guideways 13 at the ends with the slots 80 18 engaging the pins 14. The turned-over portions of the blotter strips are thus compressed against the upper face of the body portion 10 and the strips thereby firmly held in position upon and beneath the body. 85 No portion of the metal comes in contact with the surface of the paper upon which the ruler is to be employed.

It will be noted that the heads of the pins 14 project over the adjacent edge of the 90 turned-over portion 13 of the body, and operate to slightly deflect the turned-over portion toward the upturned portion 12, thus forming an inwardly sloping socket within the guideway at the ends as shown in Fig. 3, 95 to cause the upturned portions 17 of the clamp devices to be compressed when forced into the sockets, and thus assist in holding them in position.

The improved device saves time and labor 100 as means is provided for blotting the ruled lines as fast as made and by the same device which guides the ruling pen. The operator can thus immediately blot the ruled line without laying down the pen, and a plurality of ruled lines may thus be very expeditiously made. The blotting element forms a rough surface in contact with the paper to be ruled, thus materially assisting the operator in actuating the ruler, and 110 preventing it from slipping.

The blotters may be readily renewed when

required by simply detaching the clamp devices.

If required the slots 18 may be slightly inclined to the plane of the body portions 5 15 of the clamp devices, thereby increasing the grip of the clamp devices upon the blotter strips. A plurality of the blotter strips will generally be employed and superimposed, so that when one strip is used up it 10 may be detached and the next strip utilized, or the used-up strip may be cut loose at the ends leaving all of the over-turned portions beneath the clamp devices until all are used. Thus all of the blotting strips may be used 15 without detaching the clamp devices.

Having thus described the invention, what is claimed as new is:

1. A device of the class described comprising a body having a rule edge and a 20 longitudinally directed upstanding guide, and clamp devices each including a bearing portion and an upstanding guide engaging portion, the bearing portion being adapted to support a blotting element against the 25 under face of the body.

2. A device of the class described comprising a body having a rule edge and a longitudinally directed upstanding flange terminating in a guide, stop pins extending 30 from said flange, and clamp devices each including a bearing portion and an upstanding guide engaging portion, said guide engaging portion having a slot to engage said 35 pin and the bearing portion being adapted to support a blotting element against the under face of the body.

3. A device of the class described comprising a body having a rule edge and a

longitudinally directed upstanding flange terminating in a guide, clamp devices each 40 including a bearing portion and an upstanding guide engaging portion, and a portion of a blotting element between said bearing portion and the upper face of the body and retained thereby in contact with the lower 45 face of the body.

4. A device of the class described comprising a body having a rule edge and provided with a longitudinally directed upstanding flange the free edge of which is 50 bent downwardly to form a guide, clamping devices each including a bearing portion having a depending lip and an upstanding portion fitting within the guide, and fastening devices extending through the upstanding 55 portions of the body and clamp devices for holding the latter in engagement with a blotter.

5. A device of the class described comprising a body portion having one longitudinal edge thereof straight and constituting a rule edge and its other longitudinal edge bent upwardly to form an upstanding portion and thence bent downwardly to form an overhanging guide, clamp devices disposed at opposite ends of the body and each comprising a bearing portion having a depending lip and an upstanding portion fitting within the guide, the inner edges of the clamp devices at the upstanding portions 70 thereof being formed with slots and fastening devices extending through said slots and engaging the upstanding portion of the body.

In testimony whereof I affix my signature. 75
ORLANDO KLING. [L.S.]
